UNITED STATES PATENT OFFICE.

WILLIAM H. MUZZY, OF DAYTON, OHIO, ASSIGNOR TO THE NATIONAL CASH REGISTER COMPANY, OF DAYTON, OHIO, A CORPORATION OF OHIO, (INCORPORATED IN 1906.)

RECORDING DOOR-LOCK.

1,010,675.

Specification of Letters Patent.

Patented Dec. 5, 1911.

Application filed October 18, 1907. Serial No. 398,047.

To all whom it may concern:

Be it known that I, WILLIAM H. MUZZY, a citizen of the United States, residing at Dayton, in the county of Montgomery and State of Ohio, have invented certain new and useful Improvements in Recording Door-Locks, of which I declare the following to be a full, clear, and exact description.

This invention relates to improvements in recording locks and has more particular relation to improvements in door locks.

The principal object of this invention is to provide a lock of this class with permutation devices for controlling the operating mechanism and the designating recording devices.

Another object of this invention is to have the recording devices that are controlled by the clock mechanism independent of said mechanism until an impression is to be taken so that they will have no retarding influence upon the clock mechanism.

With these and incidental objects in view the invention consists in certain novel features of construction and combinations of parts, the essential elements of which are set forth in appended claims and a preferred form of embodiment of which is hereinafter specifically described with reference to the drawings which accompany and form part of this specification.

Of said drawings, Figure 1 represents a front elevation of the lock with the cover removed. Fig. 2 represents a vertical transverse section through Fig. 1. Fig. 3 represents a detail horizontal section of the permutation devices and the type wheel set thereby. Fig. 4 represents an enlarged detail front elevation of a pair of disks forming a part of the permutation devices. Fig. 5 represents a detail side elevation of the disks shown in Fig. 4. Fig. 6 represents a detail side elevation of a part of the clock train showing the winding device in section. Fig. 7 represents a detail front elevation of one of the step cams operated by the clock train and its co-operating type wheel, and Fig. 8 represents a detail front elevation of the character printing wheel and the means for setting same.

This invention is chiefly designed for use on doors of commercial establishments, for recording the time of the arrival or departure of the different clerks and also a des-

ignating character to identify the several clerks. Permutation devices control the setting of the identifying type carrier while the time type carriers are controlled by step cams which are driven by clock mechanism. The permutation devices in connection with a key which is inserted in an operating knob control the mechanism so that if the devices have been properly set and the key inserted the knob may be rotated to take an impression from the type carriers upon a record strip which in connection with an inking ribbon fed forward just before an impression is taken, after which the locking bolt will be thrown or withdrawn, depending upon the direction in which the knob is rotated. The hour step cam controls the operation of an ante-meridian and post meridian type carrier and also a day type carrier which, in connection with a month type wheel that is manually operated, are arranged to record upon the record strip in alinement with the time and identifying type carriers. The permutation devices are so designed as to allow the taking of an impression from the type carriers, but at the same time to prevent the operation of the bolt, as for instance, when it is desired to record the visit of a watchman.

Having described in general terms the operation of the lock, a more specific description will now be given.

In the accompanying drawings 1 represents the casing which surrounds the recording devices, and 2 a section of a door to which it is secured. Within the casing 1 is mounted an ordinary clock train with escapement, see Figs. 2 and 6, of which 3 represents a gear driven by a main spring 4, one end of which is secured to a shaft 5, while its other end is attached to the gear 3. This gear meshes with a pinion 6 which is secured to a shaft 7, and to which is fastened a pinion 8 that meshes with a gear 9 which is mounted upon a shaft 10. This gear 9 carries a pinion 11 which meshes with a gear 12 fast to one end of a sleeve 13 mounted upon the shaft 7, and to the other end of which is fastened a step cam 14. Fastened near the outer end of the shaft 7 is a step cam 15 for controlling the setting of the minute type carrier, while the cam 14 controls the hour type carrier as hereinafter described. The gear construction is such as

to give the stem cam 14 one twenty-fourth of a revolution to every complete revolution of the step cam 15.

The time recording devices comprise a pair of type wheels which are rotated by spring drawn rack bars to bring to the printing position type corresponding to that represented by the position of the previously described step cams which control said rack bars. As shown in Figs. 2 and 7, the hour and minute type carriers, 16 and 17 respectively, are provided with pinions 18 which are arranged to be engaged by vertical spring drawn rack bars 19. Each one of these bars is provided with a foot 20, see Fig. 1, which extends under a projection 21 formed upon a slide 22 which is guided by slot and pin connections 23. The upper end of the slide is provided with a platen 24. This slide is provided with two pins 25 and 26 which are arranged to be engaged by a disk eccentrically mounted upon the shank 28 of a door knob 29, see Fig. 2. This knob 29 is normally locked by tumblers 29^a and is released by the insertion of a suitable key 30. As the knob 29 is turned the disk 27 cams the slide 22 upwardly, allowing the rack bars 19 also to move upwardly by their springs 31. As the greatest movement of the rack bars 19 is considerably less than the movement imparted to the slide 22, it will be seen that the said bars and the type carriers 16 and 17 actuated thereby will be at rest when the platen 24 takes an impression from said type carriers.

As the slide 22 is cammed upwardly, a spring pawl 32 attached thereto, engages a ratchet 33 fastened to one end of a sleeve 35 which surrounds a shaft 36 projecting outwardly from the inner portion of the casing 1. To this sleeve is fastened one end of a record strip 37 which is fed over guide pins 37^a from a supply roll 37^b. A pinion 34 is also secured to the sleeve 35 and meshes with a similar pinion 38 mounted loosely upon a stub shaft 38^a. An absorbent ink roller 39 surrounds the shaft 38^a and is attached to the pinion 38. A ribbon 40 passes around the roller 39 and guide pins 40^a and between the type carriers and record strip. It will be seen from the above description that at the beginning of the upward movement of the slide 22, the record strip 37 and the ink ribbon 40 will be slightly advanced, and at the end of said movement the platen 24 will take an impression upon the record strip from the type carriers. As the slide 22 returns toward normal position, the pawl 32 will spring over the teeth of the ratchet 33, the latter being held in its advanced position by a pawl 33^a. Projecting from the disk 27 is a pin 41, which is arranged to engage with a vertical arm 42 of a bell crank slide 43 just before the disk 27 forces the platen 24 into contact with the

type carriers to take an impression therefrom.

If the permutation devices hereinafter described have been properly set the pin 41 will move the slide 43 to the right against the tension of its spring 44. This sidewise movement of the slide 43 will cam a spring drawn slide 46 upwardly by means of the walls of a V shaped notch 45, formed in the horizontal arm of the slide to receive the lower wedge end of the slide 46. The upper end of the slide 46 is provided with a lateral extension 47 which, when the slide is raised, enters notches formed in disks comprising a part of the permutation devices hereinafter described. The slides 43 and 46 are secured to the casing by suitable slot and pin connections. Projecting from the disk 27 is another pin 50 which is arranged to engage with a slide 51 and force it upward, so as to raise the stud 52 formed thereon out of engagement with one of the notches 53 formed upon the shank 54 of the bolt 55. The continued rotation of the disk 27 will bring the pin 50 into engagement with one side of a slot 56 formed in the aforesaid shank 54 and draw the bolt 55 out of engagement with its keeper (not shown.) Upon the movement of the disk 27 in the opposite direction the pin 50 will engage the other side of the slot 56 and force the bolt into locking position.

It will be seen from the above description that as the knob 29, shown in dotted lines Fig. 1, is rotated in the direction of the arrow in said figure, the disk 27 will be rotated in the same direction, thereby camming the platen 24 upward. As the slide 22 moves upwardly the spring 32 carried thereby will engage the ratchet 33 and feed the record strip and ink ribbon forward. Just before the platen takes an impression from the type carriers the pin 41 carried by the disk 27 will engage the vertical arm 42 of the bell crank 43 and slide it to the right in said figure against the tension of its spring 44. The bell crank as it moves toward the right will cam the slide 46 upwardly as described thereby carrying the lateral extension 47 of said slide into the notches of the permutation devices. The continued rotation of the knob will throw the bolt, the lug 52 of the slide 57 then dropping into the notch 53 of the shank 54, thereby locking the bolt from accidental movement. After the taking of an impression and the withdrawal of the bolt the disk 27 will cam the slide 22 carrying the platen 24 downwardly engaging the pin 25 projecting from the slide, which in turn will withdraw the rack bars 19 from contact with the step cams 14 and 15 and hold them in their lowered positions. In the meantime the pin 41 having passed out of engagement with the arm 42 of the bell crank 43, the latter will be drawn back to

its normal position by the spring 44, as will also the slide 46 by its spring.

The permutation devices comprise a plurality of adjustable dials which must be properly set before the operating knob can be turned far enough to cam the platen into contact with the type carriers or operate the locking bolt. These devices also control the setting of a character type carrier so that 5 when they are properly set and an impression taken, a character identifying the operator as well as the time will be recorded upon the record strip. Referring now to Figs. 3 and 4, it will be seen that the said 10 devices comprise dials 56 which are secured to the outer ends of sleeves 57 and 58 and shaft 59, the other end of said sleeves and shaft being provided with disks 60 each one of which is equipped with three deep notches 20 61 and one shallow notch 62. Adjacent to these disks are disks 63 of the same size which are loosely mounted upon the shaft or sleeves. These disks are provided with one deep and one shallow notch, 64 and 65, 25 similar to the slots 61 and 62 respectively, and are arranged to be secured to the disks 60 by means of a double tenon 66, which enters mortises 67 and 68 formed in the disks 60 and 63 respectively, as shown in Fig. 5. 30 The objects of the disks 63 is to enable the proprietor to change the combination when desired by simply withdrawing the tenon 66 and rotating the disk 60 sufficiently to bring another one of the slots 61 to register with 35 the slot 64 formed upon the disk 63. When the slots 61 and 64 register, the tenon 66 is inserted into the companion mortises 67 and 68. The casing 1 is provided with an opening 69, see Fig. 1, through which the proprietor may change the combination whenever desired. An arm 70 formed upon the lid 71 normally closes this opening. This lid is secured to the casing by means of a lock 72. A cyclometer may be secured to 40 this lid so as to register the number of times the lid has been removed and in this way enable the proprietor to know if the recording device inclosed within the casing has been tampered with. The shallow recesses 50 62 and 65 formed upon the said disks are to enable the watchman to record his visits without throwing the bolt in the following manner: He inserts his key 30 in the knob 29 which releases said knob and allows same 55 to be turned. The pin 41 formed upon the disk 27 will engage with the arm 42 of the bell crank 43 and force the same slightly to the right sufficient to allow the disk 27 to force the platen 24 into engagement with 60 the type wheels. This movement of the bell crank to the right is not sufficient to allow a full turn of the knob 29 because the watchman's combination sets up the reduced recesses 62 and 65 formed on the plates 60 and 65 68 respectively, thereby limiting the move-

ment of the slide 46 so as to prevent the pin 41 from passing the arm 42 of the bell crank slide 43. The above described permutation devices also control a type carrier 92, see Figs. 2 and 3, for recording the initial or 70 any other suitable character, so as to designate or identify the operator of the lock. This type carrier is fast to one end of a short shaft 93, the other end of which carries a pinion 94 that meshes with a pinion 95 attached to the innermost disk 60. While only one of the dials 56 operates the type carrier 92, it is to be understood that the other dials 56 will have to be properly set before an impression can be taken. 75

In order to remove all uncertainty, which may arise on account of the duplicate set of types, carried by the hour type carrier, as to whether the lock was operated before or after 12 M., a type segment is provided to 80 record ante-meridian and post-meridian and is controlled by the hour type carrier. This type carrier which is designated by the numeral 16, see Fig. 2, is fastened to one end of a short shaft 73 by means of a spline 74, 85 the other end of said shaft having secured to it a single toothed disk 75 and a disk 76 provided with a cut out portion 77, see Fig. 7. This shaft is mounted in a frame work 73^a which is secured to the sides of the casting 1. Mounted upon a shaft 89 and in the same vertical plane as the disk 76, is a disk 78 provided with concave portions 79 arranged to engage with the periphery of the disk 76 and thereby lock the disk 78 and a 90 type segment 80 secured thereto from any accidental movement. This segment 80, at its lower end, carries types A and P representing anti-meridian and post-meridian, and at its upper end is provided with teeth 95 which are arranged to be engaged by the single tooth formed upon the disk 75 and thereby rotate the segment 80 to bring the proper type in position to be recorded. When the platen is cammed upwardly, as previously described, the rack bars 19 will follow the same, thereby rotating the type carriers 16 and 17 until the upper ends of said bars contact with the steps upon the cams 14 and 15. If the time to be recorded is 100 110 A. M. the single tooth disk 75, which is connected to the hour type carrier 16, will not engage with the teeth of the type segment 80 and consequently the letter A which is normally in printing position will be recorded upon the strip; while if the time to be recorded is P. M. the disk 75 will be rotated far enough to turn the segment so as to bring the letter P into printing position. The duplicate types in the wheel 16 115 120 may be heavy and light so as to indicate ante-meridian and post-meridian if desired.

The shaft 89 upon which the disk 78 and the type segment 80 are loosely mounted, has secured to it a type carrier 82 for re- 130

cording the day of the month. This carrier is rotated automatically by a cam 84 secured to the hour step cam 14, which engages the upper end of a spring pressed arm 85, the lower end being pivoted to the casing 1. Pivoted to this arm 85 is a pawl 86 which engages a ratchet wheel 87 secured to the type carrier 82. It will be seen from this construction that upon a complete revolution of the cam 84, which occurs once every twenty four hours, the type carrier 82 will be advanced one space. A spring pressed pawl 87^a prevents any retrograde movement of said type carrier. As the days of the different months vary it will be necessary to set this printing wheel by hand at the beginning of each month, which is done by means of a pointer 88 fast to one end of the shaft 89. The month printing wheel is set by means of a similar pointer 90 which is secured to a sleeve 91 that surrounds the shaft 89, the other end of said sleeve carrying a month printing wheel 83. These pointers play over a dial 91^a which is provided with two circles of numerals, one reading from one to twelve for the months and the other from one to thirty one for the days.

Referring now to Fig. 6, it will be seen that the rewinding shaft 5 is provided with a square head 96 which fits into a recess formed in a barrel 97 of a lock casing 98. This barrel is provided with plunger pins 99 which coöperate with drivers 99^a mounted within the casing 98 to prevent any movement of said barrel and consequently the rewinding of the main spring 4 unless the proper key 100, which is carried by the proprietor or some authorized person, has been inserted. By this means prejudiced employees are prevented from putting the clock mechanism out of working order by winding the main spring too tight.

Having described the invention in detail a brief description of its operation will now be given and the different parts designated by their reference numerals. After the insertion of the key 30 and the setting of the dials 56 the operating knob 29 will be turned, which through the disk 27 and the pin 26 will cam the slide 22 and the platen 24 carried thereby upward. As the slide 22 moves upwardly rack bars 19, normally held down against the tension of their springs 31 by projection 21 of the slide extending over the feet 20 of the rack bars, will follow said slide until their upper ends contact with the step cams 14 and 15, after which the platen will be forced into contact with the type carriers to take an impression upon the record strip 37 through a inking ribbon 40. Just previous to the taking of an impression the pawl 32 carried by the slide 22 will engage a ratchet 33 and feed the record strip, and through the pinions 34 and 38 also feed the ribbon. In the meantime a pin 50 pro-

jecting from the disk 27 will elevate the slide 51 and just after taking the impression will contact with one side of the slot 56 formed in the shank 54 and operate the bolt 55. The continued rotation of the knob will, by the disk 27 engaging the pin 25, lower the slide and thereby withdraw the actuating racks 19 so as to free the clock mechanism of any retarding influence that the actuators would have if driven directly by said mechanism.

In a device of this kind, where it is used to record the arrival and departure of persons, it is very essential that the clock mechanism be as accurate as possible and by having the time recording devices normally independent of the clock mechanism there is less danger of said mechanism going wrong.

By the use of permutation devices for controlling the setting of the special type carrier a greater number of people may operate the lock than if the type carrier was differentially adjusted by the insertion of different shaped keys. Further, with all key locks the clerks may lose their keys or leave without turning them in and, in this case, the proprietor does not know who might enter his store after it is closed.

On account of the hold one may secure in the knob, the operation of the bolt and the impression devices is made much easier than if they were operated by keys as is the case in some machines on the market.

While the form of device here shown and described is admirably adapted to fulfil the objects primarily stated, it is to be understood that it is not desired to confine the invention to the one form of embodiment here disclosed, for it is susceptible of embodiment in various forms all coming within the scope of the claims which follow.

What is claimed is:

1. In a machine of the class described, the combination with a time printing mechanism, and a platen for taking impressions therefrom, of a locking bolt, a hand operated knob having connections to operate both said bolt and said platen, key controlled means normally preventing actuation of said knob, and permutation means adjustable to prevent or permit actuation of said knob.

2. In a machine of the class described, the combination with a printing mechanism, and a locking bolt, of a hand operated knob having connections for operating said locking bolt and taking impressions from said printing mechanism, and permutation means controlling the actuation of the locking bolt.

3. In a machine of the class described, the combination with a time printing mechanism, and a locking bolt, of a hand operated device having connections to operate said bolt and to take impressions from said time printing mechanism, permutation

- means controlling actuation of said locking bolt, and an identifying type carrier actuated by an element of said permutation means.
4. In a machine of the class described, the combination with a time printing mechanism, and a locking bolt, of permutation means controlling the actuation of said locking bolt, an identifying type carrier set by an element of said permutation means, and a key controlled knob having connections to actuate said locking bolt and to take impressions from said printing mechanism.
5. In a machine of the class described the combination with a printing mechanism, of a permutation lock controlling the same, means for changing the combinations of the said lock, a bolt, and device for operating the bolt and the printing mechanism.
6. In a machine of the class described, the combination with a recording mechanism, of a locking bolt, means for successively operating both said recording mechanism and said bolt, and devices for obstructing said operating means after the same has operated said recording mechanism but before operation of said locking bolt.
7. In a machine of the class described, the combination with a clock mechanism and time recording devices controlled by said clock mechanism, of permutation devices comprising a plurality of elements adjustable separately, an identifying type carrier controlled by said permutation means, devices for taking impressions from both said time recording devices and said identifying type carrier, and mechanism preventing operation of said impression devices until all said permutation elements have been properly adjusted.
8. In a device of the class described, the combination with a clock mechanism, of time recording devices controlled thereby, permutation means comprising a series of dials, an identifying recording device controlled by the latter, means for taking an impression from both of said recording devices, and means controlled by the permutation means for controlling the operation of the impression taking means.
9. In a machine of the class described, the combination with a time controlled and an identifying recording device, of key controlled devices for taking impressions from both said recording devices, permutation means comprising elements separately adjustable and connections preventing actuation of said impression taking devices until said permutation elements have been properly adjusted.
10. In a recording lock the combination with time and identifying recording devices, of a platen for taking an impression from said devices, a knob for controlling the operation of the platen, and permutation de-
- vices for controlling the operation of the knob.
11. In a recording lock, the combination with time and identifying recording devices, of a platen for taking an impression from said devices, a knob for controlling the operation of the platen, and a key lock and permutation devices for controlling the operation of the knob.
12. In a recording lock, the combination with time and identifying type carriers, of a locking bolt, means for taking an impression from said carriers and operating the bolt, and means for preventing the operation of the bolt while permitting the taking of an impression.
13. In a recording lock, the combination with time and identifying type carriers, of a locking bolt, a platen for taking an impression from the type carriers, a knob for controlling the operation of the platen and the bolt, and means for preventing the operation of the bolt while permitting the operation of the platen.
14. In a recording lock, the combination with a clock mechanism, of type carriers, actuators for said type carriers normally disengaged from the clock mechanism but controlled by the same, an identifying type carrier, a locking bolt, a platen for taking an impression from said type carriers, a knob for operating the platen and the bolt, and permutation devices for controlling the operation of the knob and the identifying type carrier.
15. In a device of the class described, the combination with time controlled devices, of time printing type carriers and actuators therefor, a locking bolt, and mechanism for causing said actuators to be driven into engagement with said time controlled devices and for thereafter actuating said locking bolt.
16. In a recording lock, the combination with a clock mechanism, of type carriers, actuators for said type carriers normally disengaged from the clock mechanism but controlled by the same, means for taking an impression from said carriers and permutation devices for controlling said means.
17. In a recording lock, the combination with a clock mechanism, of type carriers, actuators for said type carriers normally disengaged from the clock mechanism but controlled by the same, means for taking an impression from said carriers, and permutation devices and a key lock for controlling said means.
18. In a recording lock, the combination with a clock mechanism, of type carriers, actuators for said carriers normally disengaged from the clock mechanism but controlled by the same, an identifying type carrier, means for taking an impression from all of said carriers, and permutation devices

for controlling the operation of said means and the identifying type carrier.

19. In a recording lock, the combination with a clock mechanism, of type carriers, 5 actuators for said carriers normally disengaged from the clock but controlled by the same, permutation devices, an identifying type carrier controlled by the latter, a platen, means for operating the platen, and means 10 whereby the actuators set the type carriers just before the platen is operated to take an impression from same.

20. In a time recorder, the combination with a clock mechanism, of type carriers, 15 actuators for said carriers normally disengaged from the clock mechanism but controlled by the same, a type carrier for recording ante-meridian and post-meridian and

means for operating the latter controlled by the first mentioned type carriers.

21. In a recording lock, the combination with a locking bolt, of a key controlled device for actuating said bolt, devices for preventing operation of said key controlled device, permutation means comprising a plurality of notched disks, and into the notches of which said preventing devices may move, a type carrier adjusted by said permutation devices, and means for taking impressions from said type carrier.

In testimony whereof I affix my signature in the presence of two witnesses.

WILLIAM H. MUZZY.
